UNITED STATES PATENT OFFICE.

MICHAEL STRELCSIK, OF NEW YORK, N. Y.

RATCHET-DRILL.

1,198,083.

Specification of Letters Patent. Patented Sept. 12, 1916.

Application filed December 8, 1915. Serial No. 65,716.

To all whom it may concern:

Be it known that I, MICHAEL STRELCSIK, a subject of the King of Hungary, residing at Bronx, in the county of Bronx and State of New York, have invented new and useful Improvements in Ratchet-Drills, of which the following is a specification.

This invention relates to improvements in mechanism for drilling holes, and particularly to that type adapted to be manually operated, known as ratchet drills.

The principal object of the invention is to provide a device which is capable of being operated in contracted situations and combine therewith a means for forcing the drill at will into the substance in which the hole is desired.

The second object is to provide means for preventing a reverse action of the drill head when the ratchet handle is turned backward, and finally, to provide means whereby the depth of the drill can be accurately determined.

These and other objects which will become more apparent as the explanation is given, are obtained by the novel construction and combination of parts hereafter described and shown in the accompanying drawings, forming a material part of this specification, and in which;—

Figure 1 is a top plan view of a ratchet drill, showing the application of the improvements, parts being broken away in order to save space. Fig. 2 is a side elevation of the same, certain parts being broken away in order to disclose the interior. Fig. 3 is a sectional view taken on line 3—3 of Fig. 2. Fig. 4 is a detail view of the pawl and scale index, and Fig. 5 is a fragmental view, showing a portion of the side opposite to that seen in Fig. 2.

The construction of the ratchet drill in general is not unlike that of ordinary construction in which the cutting tool, as the drill bit 10 is held by the taper shank 11, in the head of drill holder 12 on which is the ratchet 13 operated by a pawl in an obvious manner as the handle 15 is actuated. The casing 16 covers the ratchet wheel and is held in position by means of flanges 17 and 18 respectively at the top and bottom of the casing, the flanges being in turn secured by nuts 19 and 20 as shown. The upper end 22 of the ratchet body 12 is bored and screw-threaded to receive the feed screw 23, the upper end of which is provided with

a hardened conical point 24, adapted to bear against any convenient rigid element, providing a thrust for the drill 10. Ordinarily, the screw 23 is furnished with the squared head or drilled holes, whereby it can be actuated by a suitable wrench or pin so as to keep the drill 10 tightly against the material to be drilled. In these improvements the ratchet 25 is rigidly secured to the top of the screw 23 on the squared portion 26, while below the ratchet is a polygonal surface 27, adapted to receive the wrench, when relieving the pressure on the drill at such times, as may be required, as at the end of the drill operation.

A casing 16 is shown to extend slightly toward the handle and at each side thereof near the head, one of the sides being fitted to receive a rod 30 slidably therein, the rod being flattened upon opposite sides, one or both of which may be provided with a scale 31 readable against a pointer or index finger 32, secured to the casing 16. At the top of the rod 30 is a head 33, comprising the upper and lower flanges 34 having between them a pawl 35 adapted to engage with the ratchet 25 as by means herewith described. On top of the casing 16 is an arm 38 having a recess 39 suited to receive the flattened rod 30, the arm being held downward in position by means of an inturned element formed on the index 32. The other end of the arm 38 is pivoted at 41 to the link 42, the opposite end of which is pivotally engaged at 43 with the slide 45 secured on the upper side of the handle 15 and caused to move by contact with the lever 46 extending through the opening 47 formed near the end of the slide, the lever being pivoted at 48 and having an arm 49 extending downwardly into the handle where it engages with a slot formed in the rod 50 near its end in such manner that as the rod is moved toward the drill head, the slide will be caused to move in an opposite direction and through the link and arm cause the pawl 35 to engage with the teeth of the ratchet 25.

The pin 54 is set in the handle and extends through the slot 53 formed in the slide 45 so as to guide it in a straight line as it is operated. In order to prevent the drill from turning backward when the handle is moved in a direction reverse to that required of forcing the drill against the work, a second ratchet 60 is secured to the drill head below the end 22, and engaging with it is

a pawl 61 carried in the casing 62 which is held in place by the nut 63 and actuated by the handle 64 in an obvious manner. The position of these handles may be varied to suit the conditions under which the implement is operated, as extended oppositely or folded in parallel, one over the other.

In operation, the drill being mounted in its position so that the points shall press 10 against the work and the point 24 of the feed screw be set against an appropriate rigid lever or the like against which sufficient thrust can be obtained, the handle 15 is actuated in the usual manner. When the 15 drill is rotated sufficiently to require a further feeding or downward movement, the knob 52 is pressed inwardly, causing the pawl 35 to engage with the ratchet 25 turning the screw such part of a revolution as 20 may be desired. When the knob is released, the pawl will be removed from the ratchet and no further fitting effect to be transmitted. As the ratchet wheel 25 is caused to move up and down, the flanges 34 on either 25 side of the pawl 35 is engaged with the sides of the ratchet wheel, causing the rod 30 to move up or down as the case may be and allow a reading to be taken of the index or scale 31 when the drill is started; obviously the distance which the drill is entered into the material can be readily ascertained.

While the invention is shown as origi-

nally incorporated in the apparatus it will be quite evident that the feeding device can 35 be applied to existing apparatus by mechanics without special difficulty, as can also the lever handle and ratchet for preventing a back action of the drill.

Having thus described my invention, what 40 I claim as new and desire to secure by Letters Patent is:—

1. In a ratchet drill, the combination with the drill holding body, ratchet and operating means therefor, and a screw for feeding said drill, of a ratchet wheel secured to said feed screw, a pawl, a sliding rod upon which said pawl is rigidly mounted, means for maintaining said pawl in a uniform plane with said ratchet wheel and means for 45 moving said pawl laterally into or out of engagement with said ratchet wheel.

2. In a ratchet wheel, the combination with the body, means for rotating said body and a feed screw, of a ratchet wheel rigidly 55 affixed to said feed screw, a pawl engageable therewith, a rod upon which said pawl is rigidly mounted, a scale formed with said rod, an index finger for said scale, means for keeping said pawl normally out of engagement with said ratchet and means combined with the handle of said drill for engaging said pawl with said ratchet.

In testimony whereof I have signed my name to this specification.

MICHAEL STRELCSIK.
